DESIGN FOR A STEMMED GOBLET OR SIMILAR ARTICLE

William P. Morrison, Mount Pleasant, Pa., as-
signor to Bryce Brothers Company, Mount
Pleasant, Pa., a corporation of Pennsylvania

Application September 2, 1936, Serial No. 64,698

Term of patent 14 years

To all whom it may concern:

Be it known that I, William P. Morrison, a citizen of the United States and residing at Mount Pleasant, in the county of Westmoreland and State of Pennsylvania, have invented a new, original, and ornamental Design for a Stemmed Goblet or Similar Article, of which the following is a specification, reference being had to the accompanying drawing, forming a part thereof.

In the accompanying drawing, Figure 1 is a perspective view of a goblet showing my design and Figure 2 is a sectional view taken on line II-II of Figure 1.

It is to be understood, however, that, while I have illustrated the design of my invention as applied to a goblet, it is equally applicable to a complete line of glass stemware, including, besides goblets, glasses for cocktails, wines, cordials, and various liquids and beverages.

I claim:

The ornamental design for a stemmed goblet or similar article substantially as shown and described.

WILLIAM P. MORRISON.
